UNITED STATES PATENT OFFICE.

JAMES L. RECORD AND HIRAM J. CAMPBELL, OF MINNEAPOLIS, MINNESOTA,
ASSIGNEES TO MINNEAPOLIS STEEL & MACHINERY CO., OF MINNEAPOLIS,
MINNESOTA, A CORPORATION OF MINNESOTA.

WHEEL.

Application filed August 11, 1919. Serial No. 316,807.

To all whom it may concern:

Be it known that we, JAMES L. RECORD and HIRAM J. CAMPBELL, citizens of the United States, and residents of Minneapolis, county 5 of Hennepin, State of Minnesota, have invented certain new and useful Improvements in Wheels, of which the following is a specification.

This invention relates to improvements in 10 vehicle wheels of the sheet metal type.

An object of this invention is to provide a strong, durable sheet metal vehicle wheel.

Another object is to provide such a sheet metal wheel, the parts of which lend themselves to rapid quantity production.

Other objects of the invention will more fully appear from the following description and the accompanying drawings and will be pointed out in the annexed claims.

20 In the accompanying drawings, there has been disclosed a structure designed to carry out the objects of the invention, but it is to be understood that the invention is not confined to the exact features shown, as various 25 changes may be made within its reasonable scope.

Figure 1 is a sectional view on the line 1—1 of Figure 2,

Figure 2 is a partial view in side elevation 30 of an assembled wheel,

Figure 3 is a sectional view on the line 3—3 of Figure 2.

This selected embodiment of the invention broadly includes a wheel made of two sheet 35 metal sections preferably of pressed sheet steel. These may easily be produced by shaping with dies on a hydraulic press. As shaped each section is provided with a hub portion, spoke portions, and a rim portion.

40 These two sections are adapted to be secured together and fastened to a hub. The hub employed is preferably a solid one, not of sheet metal, but of cast iron. The wheel may be reinforced by means of a sheet metal disk 45 disposable between the two sections, secured to each and to the hub.

The two sections of this novel wheel are alike and each has a hub portion 1, shaped to provide an annular recess so that when the 50 two complementary sections are assembled they cooperatively form an inwardly presented annular recess. Each section is cut away and the remainder is shaped to provide a plurality of spoke portions 2. And, while

the spoke portions of two complementary sections may be secured together in any suitable way it is deemed preferable to form each spoke portion with a flange 3 along its edge. The rim portion 4 of each section is shaped to form the rim of the wheel in conjunction with its opposed complementary section. Each rim portion 4, adjacent a cut-away portion—as shown in the upper part of Figure 1—is formed with a flange 5. These spoke and rim flanges provide a means whereby the two opposed sections may be secured together.

Preferably this novel wheel is reinforced, medially, by means of a disk. Such a disk 6 is disposable intermediate two opposed sections when they are in assembled position. This flat disk is cut away similarly to the sections but is not shaped out of its plane as it passes between the assembled spoke-forming portions. When this disk member is employed, the flanges of the spoke portions and of the rim portions of the assembled sections are secured to opposite faces of the disk. This securing of the sections to the disk is preferably effected by means of spot welding 80 which provides a neat and practically homogeneous joint between the three sheet metal parts.

The solid hub 7 is adapted to be received within the annular recess cooperatively presented by the hub portions 1 of two complementary sections. When the disk 6 is employed, the hub 7 is preferably formed with an annular reduced portion 8 upon which the centrally apertured disk 6 is received. 90 A bushing 9 is next fitted on the reduced portion 8 of the hub and is pressed against the adjacent face of the disk to retain the disk in position. The end face of the bushing is flush with the end face of the hub and against the thus-formed end face of the hub on this side and the end face of the hub on the opposite side, the two inner faces of the recessed hub portions 1 of the complementary sections are placed. Preferably rivets 100 10 are passed through the sections, bushing, disk and hub, and countersunk in the sides of the hub portions of the sections. These parts are all thereby held in relatively immovable position.

The periphery of the disk 6 forms a portion of the rim of the wheel. The rim portions of the two sections are preferably

joined to the sides of the disk adjacent its periphery by a butt welded joint. The rim of the wheel is preferably formed by the two rim portions and the periphery of the 5 disk.

This invention not only provides a strong, durable wheel but also one which can be economically produced in quantity. In rapid assembly, the countersunk rivets are 10 passed through the recessed hub portion of one of the sections and the cast iron hub is set on over the rivets. The disk is then put on the reduced portion of the hub, after which the cast iron bushing is put on, and 15 lastly the recessed hub portion of the complementary section is positioned. The rivets are then secured by a riveting machine and the wheel is then spot welded around the spokes and rim portions and butt welded 20 at the junction of the disk and edges of the rim portions of the two sections.

It is to be understood that the construction disclosed herein is illustrative, but not restrictive and that the same may be modified within the meaning and scope of the 25 claims which follow.

Having thus described our invention, what we claim as new, and desire to secure by Letters Patent, is:

30 1. In a metallic wheel, the combination of a pair of opposed sheet metal sections, each having a hub portion, spoke portions and a rim portion, a disk disposed intermediate the opposed sections and adapted to be secured to both said sections; a disk-like hub having a cylindrical, reduced portion extending axially to one side and on which 35

the disk is positioned against the disk-like portion of the hub, and a collar arranged on said hub reduced portion against the opposite 40 side of the disk to retain the disk in position; the outer face of the collar and the outer face of said hub reduced portion being flush, the hub portions of the two sections being shaped co-operatively to present 45 an annular recess when the sections are in opposed position to snugly receive said hub and collar, the hub portion of the sheet metal section which received the collar lying flat against the flush faces of the collar 50 and hub reduced portion and being formed with an opening registering with the opening of the hub.

2. A metallic wheel comprising a pair of sheet metal sections, each having a hub portion, a rim portion and connecting spoke portions; and a reinforcing disk interposed between the sections and having the spoke portions secured thereto; the peripheral marginal edges of the sections being turned 55 inwardly against the disk to form with its periphery a rim, the peripheral portion of said disk being flared over and secured to the inturned edges of said sections, to form therewith a peripheral wheel face which 60 is substantially flat transversely.

In witness whereof, we have hereunto set our hands this 4th day of August, 1919.

JAMES L. RECORD.
HIRAM J. CAMPBELL.
